UNITED STATES PATENT OFFICE.

JAMES H. WAGENHORST, OF JACKSON, MICHIGAN.

METHOD AND APPARATUS FOR MAKING WHEELS.

Application filed January 24, 1921, Serial No. 439,396. Renewed November 10, 1925.

This invention relates to a novel method of, and apparatus for manufacturing wheels and more particularly to the manufacturing of a wheel embodying a sheet metal felly in connection with either wooden or metallic spokes, and it will be understood that this felly may be shaped to receive either an automobile tire or a demountable tire carrying rim.

10 The object of the invention is to provide for mechanically expanding the sheet metal felly or fixed rim at definite points, arranging the spoke ends in connection with said felly at said points, bringing said spokes 15 into a common plane and then permitting the felly or fixed rim to contract to its normal size and shape and place all of the spokes under radial compression.

With this object in view, and certain others 20 which will become apparent as the description proceeds, the invention consists in the novel features hereinafter fully described and set forth in the appended claims.

In the drawings forming a part of this 25 specification, Fig. 1 is a vertical sectional view of one form of apparatus for carrying out my improved method, the plunger being shown raised and the spokes arranged in their initial position with reference to the 30 felly or fixed rim; Fig. 2 is a similar view showing the plunger lowered and the spokes brought into a common plane which is their final position with reference to the felly or fixed rim; Fig. 3 is a sectional plan on the 35 line 3—3 of Fig. 1 the spokes being omitted; Fig. 4 is a detailed view showing in exaggerated form the expansion or distortion of the felly or fixed rim; Fig. 5 is a detail sectional view on the line 5—5 of Fig. 2 and 40 Fig. 6 is a view of a central vertical section showing a slight modification.

In the practical embodiment of my invention I employ a suitable base or table 10 upon 45 which are arranged expanding arms or members 11, the inner ends of which are mitered as shown at 11^a and the outer ends being shaped at 11^b to receive the sheet metal felly or fixed rim 12 thereon, and the outer ends are also provided with guide ribs 13 against 50 which the felly or fixed rim contacts and between which the outer ends of the spokes 14 are placed, it being understood that the felly or fixed rim 12 is formed with tenon receiving 55 openings or sockets 12^a which receive the spoke tenons 14^a. The arms or members 11 are intended to slide radially upon the sup-

port or table 10 and are preferably formed with a dove-tail rib upon the bottom thereof which moves in a dove-tail groove in the table or support 10, and each arm or member 60 11 is formed at its inner end with a depending portion 15, the upper inner edge of which is beveled as shown at 15^a.

This beveled portion 15^a is intended to be engaged by the beveled end 16^a of the plunger 65 16 which plunger is moved vertically up and down by any suitable mechanism, and at 17, I have indicated diagrammatically a fluid pressure device for actuating this plunger.

A collar 18 is attached to the plunger 16 70 and is adapted to engage the inner and mitered ends of the spokes 14 which are initially supported upon a ring 19 held upon a coil spring 20.

Coil springs 21 are located in the table or 75 base 10 and normally bear against the depending portions 15 of the expanding arms or members and tend to hold said arms or members contracted as most clearly shown in Fig. 1.

80 After the felly or fixed rim has been placed upon the outer ends of the expanding arms or members the plunger 16 is actuated and forced downwardly and as the tapered end of the plunger comes in contact with the 85 tapered ends of the expanding arms or members said arms or members are forced radially outwardly a distance corresponding to the pitch of the taper and as these expanding arms or members are forced radially 90 outward radial pressure will be exerted upon the felly or fixed rim at those points thereby perceptibly expanding the felly or fixed rim or distorting the same by forcing the rim outwardly at the points where the expanding 95 arms or members contact therewith, and drawing the rim inwardly to a certain extent between such points, this action being shown in exaggerated form in Fig. 4.

100 Simultaneously with the expansion or distortion of the rim the spokes are brought from the inclined position shown in Fig. 1 to the position shown in Fig. 2 or in other words they are brought into the true wheel plane by the collar 18 contacting with the 105 inner ends thereof and forcing the ring 19 downwardly and compressing the spring 20 as most clearly shown in Fig. 2.

When the plunger is withdrawn or returned to its normal position the wheel can 110 be lifted off of the expanding arms or members inasmuch as the springs 21 will return

them to their normal or innermost positions the moment that the plunger 16 is withdrawn upwardly, and after the wheel is removed from the machine the coil spring 20 will of course return the spoke supporting ring 19 to its normal position, and another rim can be arranged upon the expanding arms or members and another set of spokes arranged for engagement therewith.

10 It must be understood that the felly or fixed rim is expanded or distorted at the points where the spokes are brought into engagement with said felly or fixed rim and as soon as the expanding pressure is relieved the inherent resiliency and contractile property of the rim will immediately return said felly or fixed rim to its normal contracted and circular condition and thereby placing all of the spokes under uniform radial compression.

15 In Fig. 6, I have shown a slight modification in which an expander block 25 having a tapered end 25^a is arranged centrally within the expanding arms or members 11 which arms or members are arranged substantially the same as previously described upon the supporting table or frame 10 and the felly or fixed rim 12 is arranged upon the outer ends of the expanding arms or members as 20 previously described.

25 The spoke supporting ring 26 is carried at the upper end of the rods 27 which slide in openings 28 produced in the expander block 25, coil springs 29 being wound around the rods 27 and tending to normally maintain the spoke supporting ring 26 in its elevated position. The plunger 30 has the same collar 18 connected thereto for engaging the inner ends of the spokes and bringing them 30 to a true plane. The plunger 30, however, contacts with the expander block 25 and forces the same downwardly and connected with the plunger is a kick-out member 31 connected by rods 32 so that as the plunger 35 30 is elevated the kick-out member 31 will operate upon the expanding member 25 and will raise the same so that the expanding arms or members 11 can return to their normal innermost positions; springs 21 serving 40 to accomplish this as previously described.

45 It will thus be seen that I provide a simple method of making a wheel embodying a sheet metal felly or fixed rim and spokes which may be of wood or metal, and in case 50 they are of metal they may be either solid or sheet metal as preferred.

55 By means of the above described method and apparatus I am able to quickly and easily assemble a wheel embodying these 60 characteristics and in which the spokes will be brought into the true wheel plane and subjected to the proper radial compression while held in such position, all of which is brought about by making the spokes of the proper 65 dimensions and positioning the same in the

sheet metal felly or fixed rim, mechanically expanding the felly or fixed rim at the points opposite the spoke ends, bringing the spokes into a wheel plane, and finally relieving the rim of expansion and permitting it to contract and assume its normal condition.

Having thus described my invention, what I claim is:—

1. The method of making wheels which consists in expanding a sheet metal felly at definite points and contracting said felly at intermediate points, bringing the outer ends of the set of spokes into engagement with said felly at the points of expansion and then relieving said felly of such expansion.

2. In a device for making wheels, the combination with means for holding a sheet metal felly and supporting a set of spokes, with their outer ends in juxtaposition to said felly, and means for expanding said felly at definite points contracting said felly intermediate said points and bringing said spokes into a wheel plane and into engagement with said felly while so expanded.

3. The method of making wheels which consists in arranging a set of spokes with their outer ends in juxtaposition to a sheet metal felly surrounding the same, expanding said felly radially outwardly at points opposite the ends of the spokes only, and bringing the spokes into a wheel plane while maintaining said felly in such expanded condition and then relieving said felly of such expansion.

4. The method of making wheels which consists in arranging a set of spokes with their outer ends in juxtaposition to a sheet metal felly surrounding the same, expanding said felly at points adjacent said spoke ends, only bringing said spokes into a wheel plane while said felly is so expanded and then relieving said felly of such expansion.

5. In a machine for making wheels the combination with means for engaging and expanding a sheet metal rim simultaneously at spaced points, and means for positioning a set of spokes in a wheel plane, within the sheet metal rim while so expanded, said expanding means being releasable whereby the sheet metal rim may resume its normal shape and radially compress the set of spokes so positioned.

6. In a machine for making wheels the combination with means for supporting a sheet metal felly and a set of spokes with their outer ends in juxtaposition to said felly and means for expanding said felly at points adjacent said spoke ends only, and bringing said spokes into a common plane and into engagement with said felly while so expanded.

7. In a machine for making wheels the combination with a plurality of expanding

members adapted to receive thereon a sheet metal felly and the outer ends of a set of spokes, means for supporting the inner ends of said spokes, and means for expanding 5 said members and bringing said spokes into a common plane while said members are so expanded.

8. In a machine for making wheels, the combination with a set of expanding members 10 adapted to receive a sheet metal felly at the outer ends thereof, means for expanding said members, means for supporting a set of spokes with their outer ends in juxtaposition to the sheet metal felly and with 15 their inner ends in a plane outside the plane of said felly and means for moving said inner ends into the plane of the felly while said members are expanded.

9. In a machine for making wheels, the combination with a suitable support, of a 20 series of expanding members arranged thereon, said expanding members being adapted to receive a sheet metal felly upon 25 their outer ends, a plunger for expanding said members, means for supporting a set

of spokes and means operated from said plunger for bringing said spokes into the plane of the wheel.

10. In a machine for making wheels, the combination with a suitable support, of a 20 series of expanding members arranged thereon and having their outer ends circumferentially spaced, said outer ends being adapted to receive thereon a sheet metal felly, 25 means carried at the ends of said expanding members for guiding the outer ends of the spokes, means for supporting the inner ends of said spokes, means for expanding said members and bringing the inner ends of a set of spokes into the plane of the felly. 40

11. The method of making wheels, which consists in applying force to expand a circular felly at definite spaced points, bringing the outer ends of the spokes of a spoke set 45 into engagement with said felly at the points of expansion, and then releasing said force.

In testimony whereof, I hereunto affix my signature.

JAMES H. WAGENHORST.
